(57) **CLAIM**

The ornamental design for a pot lid handle, as shown and described.

DESCRIPTION

FIG. 1 is a front perspective view of a pot lid handle showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the pot lid handle in context with a pot lid.

The broken lines illustrating the pot lid are for environment purposes only and form no part of the claimed design. Further, the broken lines in FIG. 7 depict portions of the pot lid handle that form no part of the claimed design.
